UNITED STATES PATENT OFFICE.

CHARLES H. RUGGLES, OF WEST PALM BEACH, FLORIDA.

SEA WALL.

Application filed May 26, 1924. Serial No. 715,974.

To all whom it may concern:

Be it known that I, CHARLES H. RUGGLES, a citizen of the United States, residing at West Palm Beach, in the county of Palm Beach and State of Florida, have invented certain new and useful Improvements in Sea Walls, of which the following is a specification.

This invention relates to sea walls and more particularly to walls of this character for use on salt water.

The object of the invention is to provide a wall of this character composed of wood faced with a protective coating to prevent destruction of the wood by salt waterworms and the like.

Another object is to construct a sea wall composed of sections suitably connected and which support a concrete super-structure mounted above the low water line to receive the splash and also to operate as a protector when the water is high.

With these and other objects in view, the invention consists in certain novel features of construction as hereinafter shown and described and then specifically pointed out in the claims and in the drawings illustrative of the preferred embodiment of the invention.

In the accompanying drawing:

Figure 1 is a top plan view of one section of the sea wall constructed in accordance with this invention, parts being broken out and in section.

Fig. 2 is an end elevation thereof.

Fig. 3 is a fragmentary view, in plan, upon an enlarged scale of one end of the wall.

The sea wall embodying this invention is constructed in sections or units which are exactly alike, hence one only will be described in detail. These units or sections may be of any desired length or size and each is composed of a frame or crib 1 constructed entirely of wood and designed to be completely submerged even at low water line. Each of these cribs 1 comprises a deck or base 2 composed of a plurality of boards 3 laid on and secured to sleepers or beams 4, the boards being arranged longitudinally of the section and the beams transversely. The base or deck 2 terminates at a point spaced inwardly from the front ends of the beams 4 and arranged in advance of said deck and spaced therefrom is a toe piece 5 bolted to the beams 4 and between

which and the front edge of the deck 2 is disposed an upright sheathing or wall 6 supported by upright beams or standards 7 at the bases of which and in front thereof the toe piece 5 is secured. The sheathing 6 and beams 7 completely fill the space between the front edge of the deck 2 and the toe piece.

The sheathing 6 is composed of longitudinally extended edgewise disposed boards 8 having a cementitious facing 9 arranged over a reinforcing backing 10 of mesh wire. This facing extends over the fronts and ends of the vertical beams 7 and around the ends of the sheathing boards 8 (see Fig. 3) and effectively protects said members against sea water worms and the like.

Blocks 11 are secured to the upper faces of beams 4 in advance of and adjacent to the toe piece 5 and are secured by nails or other suitable fasteners.

Braces 12 connect the upper end of the sheathing 6 with the rear portion of the deck 2 being bolted through the sheathing and the vertical beams 7. Auxiliary braces 13 connect the lower portion of the sheathing and the deck (see Fig. 2) being also bolted to the beams 7 and the deck. Any desired number of these braces may be used, one pair for each vertical beam 7 being shown.

At the rear of the sheathing 6 and spaced therefrom are posts 14 of a height corresponding to the vertical beams 7 and on the upper end of which and said beams is supported a concrete superstructure or splash member 15. This member is here shown tapered toward its upper end with its lower end extended about three inches, more or less, below the low water line, the upper ends of beams 7 and posts 14 being embedded in said structure and protected thereby while forming a support therefor.

A shutter chamber 16 is formed at the rear of the longitudinally projecting ends of the sheathing 6 and a shutter lock 17 is arranged at the rear of said chamber.

Although a wall, in accordance with this invention, is designed primarily for use on salt water, yet it is obvious that the crib can be used on fresh water and when so used the protective coating, if desired, can be dispensed with.

From the above description it will be obvious that the wooden frame or crib 1 is to be at all times submerged and consequently

the life thereof will be prolonged indefinitely. The cementitious facing operates to protect the crib against sea worms and the like, the concrete super-structure 5 protecting its upper end.

What I claim is:—

1. A wall for the purpose set forth comprising a series of horizontal sleepers, a deck secured thereon and spaced from the forward ends thereof, standards mounted on the sleepers forwardly of the deck, a sheathing positioned against the rear face of and of the same height as the standards and further abutting against the forward edge 10 of the deck, a longitudinal toe piece secured to the sleepers and abutting against the standards, a series of superposed short and long inclined braces arranged rearwardly of said sheathing and secured to the latter 15 and to the standards and further secured to the deck and sleepers, and a series of vertical posts arranged rearwardly of the sheathing and each secured to a pair of said superposed braces.
2. A wall for the purpose set forth comprising a series of horizontal sleepers, a deck secured thereon and spaced from the forward ends thereof, standards mounted on the sleepers forwardly of the deck, a sheathing positioned against the rear face of and of the same height as the standards and further abutting against the forward edge 20 of the deck, a longitudinal toe piece secured to the sleepers and abutting against the standards, a series of spaced inclined braces arranged rearwardly of and secured against said sheathing and further secured against the deck, and a series of vertical posts arranged rearwardly of the sheathing and 25 secured to said braces.
3. A wall for the purpose set forth comprising horizontally disposed sleepers, a deck secured thereon and spaced from the forward ends thereof, standards mounted on the sleepers forwardly of the deck, a vertically disposed sheathing positioned against the rear face of and of the same height as the standards and further interposed between the deck and the standards, a longitudinal toe-piece secured to the sleepers and positioned against the forward face of the standards, bracing elements secured to the rear face of the sheathing and against the upper face of the deck, and a cementitious body enclosing said standards and arranged 35 against the forward face of the sheathing.
4. A wall for the purpose set forth comprising a set of horizontally disposed spaced sleepers, a deck mounted thereon and spaced

from the forward ends thereof, standards 60 mounted on the sleepers forwardly of the deck, a vertically disposed sheathing positioned against the rear face of and of the same height as the standards and further abutting against the forward edge of the deck, a longitudinally extending toe-piece 65 secured to the sleepers and abutting against the forward face of the standards, spaced brace elements inclining downwardly and abutting against said sheathing and said deck, means extending through said standards, sheathing, and elements for securing them together, and means extending through said sleepers, deck and elements for connecting them together.

5. A wall for the purpose set forth comprising a set of horizontally disposed spaced sleepers, a deck mounted thereon and spaced from the forward ends thereof, standards 80 mounted on the sleepers forwardly of the deck, a vertically disposed sheathing positioned against the rear face of and of the same height as the standards and further abutting against the forward edge of the deck, a longitudinally extending toe-piece 85 secured to the sleepers and abutting against the forward face of the standards, spaced brace elements inclining downwardly and abutting against said sheathing and said deck, means extending through said standards, sheathing, and elements for securing them together, means extending through said sleepers, deck and elements for connecting them together, and a series of vertically disposed posts arranged rearwardly 90 of the sheathing and abutting against one side of and secured to said elements and providing in connection with the sheathing and standards a support for a splash member.

6. A wall for the purpose set forth comprising a deck, supporting means therefor projecting forwardly therefrom, spaced vertical standards mounted on said supporting means forwardly of the deck, a vertically disposed sheathing interposed between the standards and deck, inclined bracing elements between the sheathing and deck, a toe-piece mounted on said supporting means forwardly of said standards, and a cementitious body enclosing the standards and further connected throughout to the exposed portions of the forward face of the sheathing.

In testimony whereof, I affix my signature hereto.

CHARLES H. RUGGLES.
